UNITED STATES PATENT OFFICE.

DOROTHY F. WHITT, OF LOUISVILLE, KENTUCKY.

TENT-POLE.

1,330,363.

Specification of Letters Patent. Patented Feb. 10, 1920.

Application filed September 19, 1919. Serial No. 324,806.

To all whom it may concern:

Be it known that I, DOROTHY F. WHITT, a citizen of the United States, residing in the city of Louisville, county of Jefferson, 5 and State of Kentucky, have invented a new and useful Improvement in Tent-Poles, of which the following is a specification.

This invention relates to tent-poles.

Tents are shelters made of flexible material—usually canvas or other coarse woven fabric, supported by a pole or poles, and stretched by cords, or ropes, that are secured to pegs, or pins, driven into the ground, they are usually set up in clear 10 weather and the cords are drawn taut. When the canvas becomes wet, as in case of rain, it shrinks or contracts, thereby exerting great stress upon all connections and resulting at times in the breaking of the 15 cords and rending of the canvas. Consequently it is customary to loosen the cords when rain threatens. As the tent dries the parts expand to their normal condition and the cords have to be drawn taut again. At 20 times the rain comes up suddenly, or during the night, and the inmates of the tent are not inclined to go out in the rain to loosen the cords and damage results.

An object of this invention is to provide 25 means adapted to be associated with a tent pole which will keep the canvas and cordage under proper tension at all times, yielding under excess stress as it shrinks when wet and expanding and taking up the slack 30 as it dries.

Another object is to provide means such as characterized which will be economical in construction, durable and efficient in service.

With the foregoing and other objects in view the invention consists of the novel construction as illustrated in the accompanying drawing which forms a part of this specification wherein is set forth an 40 embodiment of the invention, but it is to be understood that such changes and modifications may be resorted to as come within the scope of the appended claims.

In the drawings wherein like reference 50 characters designate like parts in the several views, Figure 1, is a perspective view of a tent which is upheld by a pole embodying the invention; Fig. 2, a side elevation of a pole equipped with the invention, 55 parts being broken away and parts in section; Fig. 3, a perspective view of the re-

ceptive member of the device; and Fig. 4, a perspective view of the entrant member thereof.

The invention comprises a pair of members the adjoining ends of which overlap and are slidably engaged with each other, and a resilient element associated therewith and adapted to resist longitudinal movement of the members relative to each other in one direction. The members are preferably tubular, and are telescopically engaged, they may be of such length as to serve as a tent-pole, or they may be of a reduced length and be affixed to the ends 60 of wooden poles.

Referring now to the drawings the reference numeral —10— designates a tent of conventional design, which is upheld by a tent-pole —11— which embodies the invention. As illustrated herewith the device comprises two tubular members —12— and —13— adapted to be telescopically engaged. One of the members, as 12, is provided with a pair of oppositely disposed interior 75 grooves, or channels, each of which consists of three connected passages —15, 16 and 17— which extend respectively spaced distances longitudinally, circumferentially and then longitudinally of the tube. The 80 other, or entrant member, is provided near its end with two oppositely disposed exterior projections —18— which are adapted to be engaged in the aforesaid grooves, forming a bayonet joint whereby the members may be readily engaged and disengaged. Each member is provided intermediate its length with suitable means such as an interiorly disposed circumferential rib —19— which serve as abutments against 85 the ends of a suitable resilient element such as a coil spring —20— seat. Disks —21, are interposed between the ends of the springs and the abutments. With a spring inserted in one of the members, as 90 13, the other member is placed over it and pressure exerted thereon compressing the spring and causing the projections 18 to enter the grooves 15, until they reach the 95 passage 16 at which point a slight turn of 100 the entrant member causes the projections to enter that passage and the two members are then secured against separation. Sections of wooden poles —22— are then 105 inserted in the outer ends of the two members and secured therein by suitable means such as screws —23— which are passed

through perforations —24—. The size of the tubing and the strength of the spring is proportioned to the duty the pole is to stand, the spring being such that it will 5 support the tent covering under normal conditions without yielding, but under extra stress caused by contraction thereof, when wet, it will yield the projection sliding down the groove 17, and as the covering 10 dries and stretches it will expand thereby taking up the slack keeping it and its connections taut at all times.

The assemblage as herein described, comprising the interlocked telescoping members with the inclosed spring may be shipped to any desired point and there affixed to poles already in service thereby securing the advantages of the improved device without incurring the expense of new 20 poles.

Having thus described the invention so that anyone skilled in the art pertaining thereto can make and use the same, I claim:—

25 1. In combination with a tent pole consisting of two sections, a pair of tubular members adapted to be affixed respectively

to opposed ends of said sections, said members adapted to be telescopically engaged, an internal annular shoulder intermediate 30 the length of each of the members, interengaging means adapted to prevent separation of the members while permitting relative longitudinal movement thereof, and an internally disposed spring seating on 35 said shoulders.

2. In combination with a tent pole comprising two sections, a pair of telescopic members adapted to be affixed respectively to the opposed ends of said sections, the 40 recipient member having a pair of diametrically opposed internal grooves extended inward from the free end thereof longitudinally a spaced distance then circumferentially a spaced distance then longitudinally a spaced distance, a pair of diametrically opposed exterior projections on the entrant member adapted to be engaged in said groove, an internal annular shoulder intermediate the length of each of the 45 members, and a spring disposed within the members and seating on said shoulders.

DOROTHY F. WHITT.
